DISPENSING NOZZLE GUARD

Glenn E. Moore, Fairfield, Ohio, assignor to Dover Corporation, Cincinnati, Ohio, a corporation of Delaware

Filed Mar. 30, 1964, Ser. No. 79,259

Term of patent 14 years

(Cl. D91—1)

FIG-1

FIG-2

FIG-3

FIG-4

FIG-5

FIGURE 1 is a perspective view of a dispensing nozzle guard embodying my new design;

FIGURE 2 is a side elevational view thereof;

FIGURE 3 is a front elevational view thereof;

FIGURE 4 is a top plan view thereof;

FIGURE 5 is a rear elevational view thereof.

The dominant features of my design reside in the portion shown in full lines and the dispensing pump handle and nozzle, depicted in broken lines, are for illustrative purposes only.

I claim:

The ornamental design for a dispensing nozzle guard, as shown and described.
